UNITED STATES PATENT OFFICE.

DANIEL DRAWBAUGH, OF EBERLY'S MILL, PENNSYLVANIA, ASSIGNOR TO THE DRAWBAUGH TELEPHONE AND TELEGRAPH COMPANY, OF NEW YORK, N. Y.

TELEPHONE-TRANSMITTER.

SPECIFICATION forming part of Letters Patent No. 540,781, dated June 11, 1895.

Application filed February 16, 1895. Serial No. 538,694. (No model.)

To all whom it may concern:

Be it known that I, DANIEL DRAWBAUGH, of Eberly's Mill, in the county of Cumberland, State of Pennsylvania, have invented certain 5 new and useful Improvements in Telephone-Transmitters; and I do hereby declare the following to be a full, clear, and exact description of the same, reference being had to the accompanying drawings, forming a part of 10 this specification, and to the letters of reference marked thereon.

This invention relates to improvements in telephonic transmitters and particularly to that type in which comminuted material of 15 low conductivity is employed as the resistance varying medium, the objects of the invention being, primarily, to provide a highly efficient instrument capable of universal use either as a long distance or local exchange 20 instrument.

A further object is to produce an instrument of exceedingly simple design whereby the manufacture is facilitated and whereby the device is prevented from getting out of 25 adjustment either through non use, rough handling or the ordinary wear and tear of use.

Referring to the accompanying drawings, Figure 1 is a front elevation of a transmitter embodying my present invention. Fig. 2 is 30 a bottom plan view of the shelf on which it is mounted. Fig. 3 is a vertical section through the support, looking toward the front. Fig. 4 is a vertical section from front to rear through the operative parts and mouthpiece 35 of the transmitter. Fig. 5 is a view with the back plate removed. Fig. 6 is a section through a modified form of diaphragm.

Like letters of reference in the several figures denote the same parts.

40 I have shown in connection with my present transmitting instrument proper, by which I mean the resistance varying mechanism with its surrounding parts, a support consisting of a back board A provided with a shelf 45 B carrying the induction coil C and binding posts C' for the receiver. The back board also preferably carries the switch lever D of a well known pattern and the binding posts for the battery and line connections lettered 50 E and F respectively. The receiver and sec-

ondary of the coil are connected in multiple or the receiver is connected in a shunt around the secondary of the induction coil. The battery circuit runs from one of the posts E to the switch, thence to the primary of the coil 55 and to the metallic portion of the hollow standard G fastened on the shelf. The other battery connection passes from the other post E by an insulated conductor up through the hollow standard and is connected at the top 60 to an insulated contact g all as shown in Figs. 1 and 3.

The shape of the standard G or the employment of any standard at all is optional, as is also the particular wiring or circuit connections described insofar as the operative parts which will now be described are concerned, and, therefore, I do not wish to be limited to the particular details heretofore set forth.

The body of the transmitter proper may be 70 of any desired shape or material but in the form illustrated it is composed of a hard insulating substance for convenience made in the form of an annulus H, that is to say, it has a relatively large opening h, while at the 75 front it is slightly recessed for the reception of the diaphragm I. The latter is held in place by the cover piece K screwed down upon it so as to clamp its edge against the body H. This cover has the usual mouth piece k and 80 is itself together with the mouth piece preferably struck or spun up from sheet metal the two parts being screwed together, as shown. At the center, the diaphragm I, in the instrument shown, carries one of the electrodes to 85 be presently particularly described, and surrounding the electrode and resting against the diaphragm is a disk L of felt or similar material, preferably felt and of such external diameter as to fit into the opening in the body. The 90 rear side of the body is provided with a plate M clamped in place by screws or otherwise and the felt or fibrous material is held forward against the diaphragm with a moderate pressure so as to dampen the latter against false 95 vibration without interfering with the true or direct vibrations due to the impact of sound waves. The back plate M in the form shown carries the rear electrode and the circuit is established on the one hand through 100

- a bearing piece m on the back plate which co-operates with a similar plate m' on the standard, the two being held in adjusted position by a set screw m^2 , and on the other hand, through a contact finger m^3 secured to the body H in electrical connection with the diaphragm, and adapted to bear on the contact piece g . The receptacle for the comminuted resistance conductor, preferably 70
 10 granular carbon indicated by the letter N , is directly in the fibrous or felt pad through which an opening of just proper size for the entry of the electrodes is formed and the electrodes themselves, lettered respectively
 15 O and O' close each side of the opening forming a small chamber the walls of which by reason of their elastic nature effectually prevent any caking or packing of the comminuted resistance conductor. In the preferred
 20 construction the faces of the electrodes are of polished resistance conductor such as carbon. The carbon face of the front electrode is held by a central rearwardly extending offset i and the carbon face of the rear electrode is held
 25 by a screw P screwing through the plate M . Obviously the faces of the off-set on the diaphragm and the face of the screw may be employed without the carbon and where cheapness is desired such construction will
 30 be found efficient. In Fig. 6 I have shown a diaphragm with the off-set simply struck out from its center by which construction the diaphragm and its electrode may be formed at a single operation.
 35 While any ordinary diaphragm may be employed, I prefer to employ a diaphragm having a thickened edge as at Q whereby the diaphragm is retained under proper tension and buckling not only prevented but by simply
 40 striking and expanding the thick edge the strains may be equalized in the diaphragm and the diaphragm put under tension so as to secure the best results.
 In setting up the instrument the parts are
 45 assembled with the exception of the rear screw. Then the comminuted material is poured in and the screw inserted. The distance between the faces of the two electrodes should be regulated according to the size of
 50 the particles of comminuted resistance conductor. Thus where fine material is used there should be a space of from one sixteenth to one eighth of an inch and the comminuted material should not quite fill the chamber
 55 when the instrument is standing in vertical position. The best adjustment of the parts, however, is best determined by experimenting and thus while I have been specific in my description it will be understood that the pro-
 60 portions and relative arrangement of the sup- porting parts are susceptible of wide variations without departing from the spirit of my invention.
 The annular form of the pad of felt or simi-
 65 lar material whereby the electrodes may be located at the center of the diaphragm gives

a most perfect dampening effect without in- juring the efficiency of the instrument and this effect would be secured even though the pad did not form the chamber for the com- 70
 75 minuted resistance varying conductor.

I do not make claim herein to the employ- ment of comminuted or subdivided resistance varying conducting material, this feature of the invention, together with the general co- 75
 80 operative arrangement of electrodes and re- sistance varying medium being described and claimed in my prior application, Serial No. 111,554, filed November 12, 1883.

Having thus described my invention, what I claim as new is—

1. In a telephonic transmitter, the combi- nation with the electrodes movable toward and from each other, of a body of felt or simi- 85
 90 lar material having an opening into which said electrodes fit and work, and a comminuted resistance conductor confined thereby be- tween the proximate faces of the electrodes; one of said electrodes being attached to a dia- phragm which latter bears against the face 90
 95 of the body of felt or similar material sub- stantially as described.

2. In a telephonic transmitter, the combi- nation with the electrodes movable toward and from each other, and the diaphragm con- 95
 100 nected with one of said electrodes, of a felt pad bearing against the diaphragm and hav- ing a central opening into which the elec- 100
 105 trodes fit and work and a comminuted resist- ance conductor confined between the prox- imate faces of the electrodes by the felt pad; substantially as described.

3. In a telephonic transmitter, the combi- nation with the body having the central open- 105
 110 ing, the diaphragm and rear plate, of the elec- trodes, a felt pad held in the central opening in the body and surrounding the electrodes to form a chamber between them and com- minuted resistance conductor located in the 110
 115 chamber; substantially as described.

4. In a telephonic transmitter, the combi- nation with the diaphragm and electrodes, of the flat elastic pad having an aperture into opposite sides of which the electrodes fit, thereby surrounding the electrodes to form a 115
 120 chamber between them and bearing against the diaphragm and the plate on the rear side of the pad for holding it in contact with the diaphragm; substantially as described.

5. In a telephonic transmitter, the combi- nation with the body having the central open- 120
 125 ing, the diaphragm and rear plate, of the elec- trodes, an annular pad of felt or similar ma- terial fitting in the central opening surround- ing the electrodes to form a chamber between 125
 130 them and filling the space between the dia- phragm and rear plate, whereby the dia- phragm is damped and comminuted resist- ance conductor located in the chamber; sub- stantially as described.

6. A diaphragm for telephonic transmitters having a rearwardly extending central offset

constituting an electrode; substantially as described.

7. In a telephonic transmitter, the combination with a diaphragm having a central rearwardly extending off-set constituting an electrode, of a pad of felt or similar material surrounding said electrode, a second electrode projecting into the said pad from the rear and comminuted resistance conductor located between the electrodes; substantially as described.

8. In a telephonic transmitter, the combination with the body and diaphragm carrying one electrode, of the pad of felt or similar material, having the central opening forming a chamber, the adjustable electrode working into said chamber and comminuted resistance conductor located in the chamber between the electrodes; substantially as described.

9. In a telephone transmitter, the combination with the body having the central opening, the diaphragm and front electrode, of the

felt pad fitting in the opening in the body and having the central opening for the electrodes, the rear plate supporting the pad against the diaphragm and the adjustable electrode passing into the pad; substantially as described.

10. In a telephonic transmitter, the combination with the body, the diaphragm electrodes and dampening pad surrounding the electrodes, of the rear plate for supporting the rear electrode, the rearwardly extending lug on said plate and a metallic support with which said lug is adjustably connected; substantially as described.

11. A diaphragm for telephones having a malleable thickened edge whereby the diaphragm may be strained by expanding the edge; substantially as described.
